UNITED STATES PATENT OFFICE.

PHILIP J. HARRAH, OF BLOOMFIELD, INDIANA.

LIFTING-JACK.

1,374,653.

Specification of Letters Patent. Patented Apr. 12, 1921.

Application filed October 4, 1920. Serial No. 414,458.

To all whom it may concern:

Be it known that I, PHILIP J. HARRAH, of Bloomfield, in the county of Greene and State of Indiana, have invented certain new and useful Improvements in Lifting-Jacks; and I do hereby declare the following to be a full, clear, and exact description of the invention, such as will enable others skilled in the art to which it appertains to make and use the same.

In Letters Patent No. 1,307,968 issued to me June 24, 1919, I have shown, described and claimed a lifting jack having a standard formed with holes extending entirely through its thickness. A pair of runners are movable on the standard and each is equipped with a spring actuated pin for alternately entering the holes of the standard to constitute a fixed stop while the other runner is advancing, a lever mechanism effecting the successive and alternate movements of the runners. The patent also covers a reversing element having means for controlling the projection and withdrawal of the pins to reverse the direction of travel of the runners.

My present improvements retain the substantial features of the patent while promoting the strength and efficiency of the device. I improve the manner of mounting the hand lever and the relative dispositions of the runners, and thereby allow the nose or step of the jack to approach close to the ground to get under low loads.

In the drawings, Figure 1 is a side elevation. Fig. 2 is a partial elevation of the reverse side. Fig. 3 is a cross section on 3—3, Fig. 1. Fig. 4 is a section on 4—4, Fig. 1, and Fig. 5 is a detail of the reversing plate. Fig. 6 shows the lower runner.

An upright standard 1 is mounted upon a suitable pedestal and formed with a vertical series of perforations 2 extending entirely through the standard so that it may be reversed when the surfaces surrounding the perforations become worn. 3 is the lower runner and 4 the upper runner. Each comprises a sleeve rectangular in cross section to correspond to the formation of the standard.

I provide a maximum bearing surface for the upper runner, this runner itself, in turn, affording an ample bearing surface for the lower runner, instead of having each runner find its only bearing in the standard, as in the patent. The upper runner substantially

incloses the lower one. Practice has demonstrated that this arrangement materially strengthens the device. The lower runner is shown formed with a pair of upright plates 3^a which bear against the edge of the standard to maintain it as against canting. The operating lever 5 is fulcrumed to the upper runner as at 6. A vertically disposed pitman 7 is fulcrumed to the lower runner 3 at 8 and to the lever at 9. In this way the pitman constitutes a movable fulcrum in the lifting action and it and the lever constitute a toggle link mechanism. When the runner 3 is fixed the fulcrum of the lever action is at 9 and when the runner 4 is fixed the fulcrum is at 6. The nose or step 10 is shown extending from the runner 4 from the side opposite to that at which the lever is fulcrumed.

The operation of the runners is substantially the same as in the patent.

I have shown the lower runner 3 apertured to receive a pin 12 having a cross arm 13 and having its outer extremity movable in a bearing formed by a bracket 14 which may be cast integrally with the runner. A spring 15 is shown coiled upon the pin and bears at one end against the cross arm and at the other end against the bracket. The tendency of the spring is to project the pin inward and into one of the perforations 2 of the standard when the pin and a perforation are in alinement. At its outer extremity the pin is beveled at its upper side as at 16. By "upper side" I have reference to the side facing the top of the standard when the device is used in an upright position. The purpose of the bevel is that when a lifting force is exerted upon the runner to draw it toward the top of the standard the beveled surface 16 will allow the pin to slide over the wall of the perforation in which it has been seated. The straight or uninterrupted formation at the opposite side of the pin, as at 17, prevents the pin withdrawing when the weight is bearing upon the runner. When the runner is to be moved downward it is necessary to effect the positive withdrawal of the pin.

The runner 4 is equipped with a pin 18, cross arm 19, bracket 20, spring 21 and beveled extremity 22 similar to the parts above described with relation to runner 3.

The perforations in the standard are so disposed that in the movement of the runners the pins 12 and 18 will not both be pro-

jected into the perforations at the same time. When one pin is projected the other pin is resting or moving on the surface between two of the perforations.

5 From what has thus far been said it will be understood that with the pin 12 of runners 3 seated in a perforation as in Fig. 4, the downward movement of the lever 5 will lift the runner 4, the weight being at point 10 6 and the fulcrum of the toggle link mechanism at 9. Runner 4 is elevated until its pin 18 snaps into a perforation. Raising the lever 5 shifts the fulcrum to the point 15 6 and the pitman 7 elevates the runner 3 until its pin 12 snaps into a higher perforation. This action is continued during the elevation of the jack.

The reversing mechanism is shown consisting of a plate 23 having appropriate 20 bearing spaces provided by the brackets 14 and 20. This plate is adapted to be longitudinally movable. It has a slotted housing 24 moving over a guide plate 25 on runner 4. A spring 26 projects into a 25 pocket in the bottom of the plate and against the lower wall of the housing. The plate is shown formed with upper and lower cam surfaces 27-28 so disposed as to be in operative relationship to the cross 30 arms 19 and 13. The reversing plate is shown formed with a flanged upper extremity 29. A cam switch 30 is pivoted on the face of the runner 4 to contact with the extremity 29 to raise the reversing plate.

35 In the lifting action the reversing plate is in the position shown, that is, elevated against the tension of its spring.

When the switch 30 is turned downward 40 so that its cam surface permits the plate 23 to drop under the tension of spring 24, the 45 cams 27, 28 will be brought close to their respective cross arms 19 and 13.

The subsequent operation of the lever 5 will cause the cross arms to ride up on the 45 cam surface and effect the positive withdrawal of the pins so as to permit the downward travel of the runners in step by step action. In this manner the toggle link mechanism which previously only permitted 50 of a raising action now allows of a lowering of the parts. By forming the standard with perforations extending entirely through its thickness it may be reversed so that the pins of the runners will operate on one or the other of its sides. After some 55 use on one side, the left as in Fig. 4, for instance, the walls around the perforations may become worn by the action of the pins. The standard may then be turned so that 60 its right side will receive the pins. This prolongs the term of usefulness of the

standard in addition to insuring ample bearing surfaces in which the pins are supported when seated.

The essential elements of my invention 65 are adapted as well for wire stretching as for wagon jacks.

By the construction herein shown and described it will be apparent that the device is materially strengthened. The 70 upper runner 4 has an extended bearing surface on the standard and as it incloses the lower runner I am enabled to place the nose or foot 10 so low that the jack may be used on any load. The relative arrangement and formation of the 75 lower runner materially aid its maintaining a correct position in its movement on the standard.

I claim as my invention:

1. A lifting jack comprising a standard 80 having a plurality of perforations extending therethrough, a pair of runners movable on said standard, the upper runner substantially inclosing and forming a bearing for 85 the lower runner, a pin carried by each of said runners for alternately entering said perforations to constitute a fixed stop while the other runner is advancing, a lever fulcrumed to one of said runners, and a pitman 90 connecting said lever with the other runner.

2. A lifting jack comprising a standard 95 having a plurality of perforations extending therethrough, a pair of runners movable on said standard, the upper runner substantially inclosing and forming a bearing for 100 the lower runner and having a nose or foot at its lower end, a pin carried by each of said runners for alternately entering said 105 perforations to constitute a fixed stop while the other runner is advancing, a lever fulcrumed to one of said runners, and a pitman connecting said lever with the other runner.

3. A lifting jack comprising a standard 110 having a plurality of perforations extending therethrough, a pair of runners movable on said standard, the upper runner substantially inclosing and forming a bearing 115 for the lower runner, said lower runner having a guiding plate bearing against said standard, a pin carried by each of said runners for alternately entering said perforations to constitute a fixed stop while the 120 other runner is advancing, a lever fulcrumed to one of said runners, and a pitman connecting said lever with the other runner.

In testimony whereof I have signed this 120 specification.

PHILIP J. HARRAH.
